ELEMIR J. NEY, OF LOWELL, MASSACHUSETTS,

ASSIGNOR TO LOWELL MANUFACTURING COMPANY.

Letters Patent for a Design No. 99, dated August 13, 1861.

SPECIFICATION.

TO ALL WHOM IT MAY CONCERN:

Be it known, that I, ELEMIR J. NEY, of Lowell, in the county of Middlesex and State of Massachusetts, have originated and designed a new Pattern for Carpets or other Fabrics, of which the following is a full, clear, and exact description, reference being had to the accompanying drawings making part of this specification.

A, in the centre, is a group of fruit and leaves resting on a plain ground. Fig. 1 is a narrow frame inclosing the ground on which rests the group A. This frame is surrounded by irregular small work.

Corners 2, 3, 4, 5, when matched, form a figure similar to A in the centre.

The bars and key-work 6 6 6 6 run between the centre and corners, and are connected at the sides and ends of the design by small rosettes.

Groups of flowers and leaves rest on the bars and key-work midway between the centre and corners.

The colors employed for the different portions of the design may be varied to suit the taste and wish of the manufacturer.

Claim.

What I claim as my invention, and desire to secure by Letters Patent, is the design or pattern for carpets or other fabrics herein set forth.

E. J. NEY.
